UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

LOCK

Application filed September 6, 1929. Serial No. 390,738.

This invention relates to certain new and useful improvements in locks and refers more particularly to that type of lock having a removable lock cylinder.

5 In locks of this character the lock cylinder is usually maintained assembled with the mounting member by cooperating means carried by the cylinder and the mounting member and which may be disabled to facilitate 10 removal and insertion of the cylinder by moving the cylinder to a predetermined position relative to the mounting member; and it is an object of this invention to provide a novel lock structure of the character described 15 wherein the usual key cooperates to prevent movement of the cylinder to its position with respect to the mounting member at which it may be withdrawn.

Another object of this invention resides in 20 the provision of yieldable means carried by the lock cylinder and movable to a position limiting rotation of the cylinder upon insertion of the regular key.

And a further object of this invention resides 25 in the provision of a special key by which the tumblers of the cylinder may be retracted without moving the yieldable means to operative position whereupon the cylinder may be moved to its position at which it is 30 removable from the mounting member.

With the above and other objects in view which will appear as the description proceeds, my invention resides in the novel construction, combination and arrangement of 35 parts substantially as hereinafter described and more particularly defined by the appended claims, it being understood that such changes in the precise embodiment of the hereindisclosed invention may be made as 40 come within the scope of the claims.

In the accompanying drawings, I have 45 illustrated one complete example of the physical embodiment of my invention constructed according to the best mode I have so far devised for the practical application of the principles thereof, and in which:

Figure 1 is an elevational view with parts 50 broken away and in section, of a lock embodying my invention;

Figure 2 is a fragmentary, perspective view of the outer end of the mounting member;

Figure 3 is a perspective view of the cylinder with a portion thereof broken away and with the regular key inserted;

Figure 4 is a fragmentary view similar to Figure 1 illustrating the position of the parts when the special key is inserted;

Figure 5 is a cross sectional view taken through Figure 4 on the plane of the line 55 5—5;

Figure 6 is a fragmentary top plan view with a portion thereof broken away and with the special key inserted;

Figure 7 is a view similar to Figure 6 with 65 the regular key inserted; and

Figures 8 and 9 illustrate the regular and special keys, respectively.

Referring now more particularly to the accompanying drawings, in which like numerals designate like parts throughout the several views, the numeral 10 represents the mounting member of my improved lock structure, having a longitudinal bore 11 counterbored at its outer end 12 and provided with a reduced bore 13 at its inner end.

A lock cylinder 14 is rotatably mounted in the bore 11 of the mounting member and is normally secured against rotation by the engagement of a plurality of locking tumblers 15 in a longitudinal groove 16 communicating with the bore 11 and extending inwardly from the counterbore 12, the tumblers being retractable to free the cylinder for rotation and the performance of its locking functions, 85 by the insertion of a key 17. To accommodate the movement of the lower ends of locking tumblers incidental to insertion and withdrawal of the key, a second longitudinal groove 18 is provided diametrically opposite 90 the groove 16.

The inner end of the lock cylinder is non-rotatably connected with an actuating element having its reduced end 20 projected through the bore 13, to provide means for imparting the locking movement of the cylinder to any desired mechanism.

The cylinder 14, after being assembled with the mounting member, is secured therein against longitudinal movement by the en-

gagement of a pin 21 carried by the mounting member, in an annular groove 22 formed in the cylinder adjacent its inner end, the engagement of the pin in the groove, however, having no effect upon the rotation of the cylinder in the performance of its locking functions.

To permit the pin 21 to be engaged and disengaged with the annular groove 22 during assembly and withdrawal of the cylinder from the mounting member, that portion of the cylinder between the annular groove and its inner end is longitudinally slotted, as at 23, to form an entrance to the groove. The groove and the slot thus together comprise a bayonet slot through which the pin may be passed whenever the cylinder is turned to align the slot with the pin 21. It is, however, desirable that the alignment of the slot 23 with the pin 21 should not take place within the normal limits of movement of the cylinder, and therefore the means defining the normal limits of movement are so arranged that under certain circumstances when it is desired to withdraw the cylinder, it may be moved beyond one of its normal limits of movement to effect the desired alignment.

The means for limiting the rotation of the cylinder comprises mounting member stops or abutments with which cylinder carried stops or abutments cooperate. The mounting member stops are formed by the ends 24 and 25 of a projection 26 extended from the bottom of the counterbore 12 and forming a continuation of the bore 11, the end 25 being a continuation of one side of the longitudinal tumbler groove 16 and the end 24 being spaced a few degrees in a clockwise direction from the corresponding side of the tumbler groove 18. The width of the projection 26 is such that its forward end engages the rear wall of an enlarged head 27 formed on the cylinder from which a portion 28 projects rearwardly throughout approximately 90 degrees, so that the ends 29 and 30 of the rearward projection form abutments which lie in the path of and are engageable with the mounting member stops 24 and 25, respectively.

The engagement of the abutment 29 with the stop 24, limits the clockwise rotation of the cylinder when it reaches its unlocked position, which is approximately 90 degrees from its locked position and thus defines one of the normal limits of movement of the cylinder. The engagement of the abutment 30 with the stop 25, however, does not define the other limit of normal movement, but arrests counterclockwise rotation of the cylinder when it reaches the position aligning its bayonet slot with the pin 21 to permit withdrawal of the cylinder. This position is beyond the limit of normal counter-clockwise movement, and to normally prevent the

movement of the cylinder to said position, an axially movable stop member 31 is provided which is normally in inoperative position, but is moved to operative position by the insertion of the regular key 17, in a manner to be later described.

The stop member 31 consists of a lug 32 riveted or otherwise secured to one end of an arcuate flat spring 33 whose other end 34 is securely fixed in a groove 35 formed in the enlarged cylinder head 27. The groove 35 is increased in width, as at 36, to accommodate axial movement of the end of the spring which carries the lug 32, and extends beyond the end 30 of the projection 28, a distance equal to the width of the tumbler groove 16 to terminate, as at 37, in line with the stop or abutment 25. The bottom of the enlargement 36 of the groove between the abutment 30 and its end 37 is flattened, as at 38, to receive the lug 32, and extends to a point in line with the rear of the projection 28 to accommodate the movement of the lug by the key 17.

When the spring 33 is in its natural position, it lies flat against the forward straight wall 39 of the groove 35 and the lug 32 lies behind the shoulder formed by the end 37 of the groove out of the path of the stop or abutment 25, but upon insertion of the regular key 17 it is moved inwardly by the engagement of an abrupt step 40 on the regular key, with an ear 41 extended downwardly from the lug 32 into the key slot 42 which communicates with the flattened portion 38, and into the path of the step on the key, when the key reaches its fully inserted position. It will be noted that the projection 41 on the lug 32, by its engagement in the key slot, guides the movement of the lug and also relieves the spring 33 of all stress incidental to tendency to turn the cylinder in a counter-clockwise direction through the key 17, by imparting such stress directly to the cylinder.

From the foregoing it is obvious that it is impossible to move the cylinder beyond the limits of its normal movement with the regular key 17, hence a special key 43 is provided whose step 44 is so located as to never engage the ear 41, whereby the spring remains unaffected by the insertion of the key to retract the tumblers. Thus with the key 43 the cylinder may be freed for rotation and turned in a counter-clockwise direction until its abutment 30 engages the abutment or stop 25. At this time the bayonet slot 23 will be aligned with the pin 21 making it possible to withdraw the cylinder by imposing an outward stress on the key.

From the foregoing description, taken in connection with the accompanying drawings, it will be readily apparent to those skilled in the art to which an invention of the character described appertains, that I provide novel

means for removably securing a lock cylinder in its mounting member which utilizes the insertion of the regular key to prevent movement of the cylinder to a position permitting its withdrawal and wherein the use of a special key frees the cylinder for rotation and permits the same to be turned to its position at which the same can be withdrawn from the mounting member.

10 What I claim as my invention is:

1. In a lock of the character described, a mounting member, a lock cylinder in the mounting member being movable therein in the performance of its normal locking functions upon insertion of a proper key, cooperating means carried by the mounting member and the lock cylinder for releasably securing the lock cylinder in the mounting member, said means becoming inoperative upon movement of the lock cylinder to a predetermined position, and means for preventing movement of the lock cylinder to said predetermined position, said means becoming operative upon insertion of the key.

2. In a lock of the character described, a mounting member, a lock cylinder movable in the mounting member in the performance of its normal locking functions, tumblers carried by the cylinder and releasable upon the insertion of a proper key, cooperating means carried by the mounting member and the lock cylinder for releasably securing the lock cylinder in the mounting member, said means becoming inoperative upon movement of the lock cylinder to a predetermined position, and cooperating means carried by the mounting member and the lock cylinder for preventing movement of the lock cylinder to said predetermined position, one of said means being movable to operative position by the insertion of the key.

3. In a lock device of the character described, a mounting member, a lock cylinder adapted to receive a key and being movable in the mounting member upon the insertion of the key, means for releasably maintaining the lock cylinder assembled with the mounting member, said means becoming disabled to permit withdrawal of the lock cylinder upon movement of the lock cylinder to a predetermined position with respect to the mounting member, and yieldably means, normally inoperative, to prevent movement of the lock cylinder to said predetermined relative position, the insertion of the key moving the yieldable means to operative position.

4. In a lock device of the character described, a mounting member, a lock cylinder adapted to receive a key and movable in the mounting member upon the insertion of the key in the performance of its normal locking functions, means for releasably maintaining the lock cylinder assembled with the mounting member, said means becoming dis-

abled to permit withdrawal of the lock cylinder upon movement of the lock cylinder to a predetermined position with respect to the mounting member, and cooperating means carried by the mounting member and the lock cylinder for preventing movement of the lock cylinder to said predetermined position, one of said means being movable to operative position by the engagement of an abutment on the key with a portion thereof during insertion of the key.

5. In a lock structure of the character described, a key controlled lock cylinder removable from its mounting member when in a predetermined position, means for preventing movement of the lock cylinder to said position including an axially movable member, means for normally yieldably maintaining the axially movable member in inoperative position, and means whereby the axially movable member is moved to operative position by the insertion of the key.

6. In a lock structure of the character described, a key controlled lock cylinder removable from its mounting member when in a predetermined position, means for preventing movement of the lock cylinder to said predetermined position and including an axially movable member, means for normally maintaining the axially movable member in inoperative position, means whereby the member is moved to operative position by the complete insertion of the key, and means for guiding the movement of the axially movable member and providing an interlocking connection with the lock cylinder to receive the stress incidental to limiting the movement of the cylinder.

7. In a lock device of the character described, a mounting member, a lock cylinder movable in the mounting member in the performance of its normal locking functions upon the insertion of a proper key, means normally maintaining the lock cylinder assembled with the locking member, said means becoming inoperative upon movement of the lock cylinder to a predetermined position with respect to the mounting member, means for preventing movement of the lock cylinder to said predetermined position and including a mounting member carried abutment, a movable member, means normally maintaining the movable member out of engagement with the abutment, means whereby the movable member is moved into engagement with the abutment by the insertion of the key to free the cylinder for movement, and means for simultaneously guiding the movement of the movable member and transferring the stress applied to the movable member by a tendency to move the lock cylinder in the direction restricted by the engagement of the movable member with the mounting member abutment.

8. In a lock structure of the character de-

- scribed, a key controlled lock cylinder removable from its mounting member when in a predetermined position, means for preventing movement of the lock cylinder to said predetermined position including an axially movable member, means for mounting the axially movable member, said means normally yieldably maintaining the same in inoperative position, and means whereby the axially movable member is moved to operative position by the complete insertion of the key. 75
9. In a lock of the character described, a mounting member, a lock cylinder movable in the mounting member in the performance of its normal locking functions upon the insertion of a proper key, means for releasably securing the lock cylinder in the mounting member without interfering with its normal locking functions and becoming inoperative upon movement of the lock cylinder to a predetermined position, means for preventing movement of the lock cylinder to said predetermined position and including an abutment carried by the mounting member, a movable member, spring means mounting the movable member from the lock cylinder and normally maintaining the same out of the path of the mounting member abutment, means whereby the insertion of the key to free the cylinder for movement moves the movable member into the path of the mounting member abutment, and means for guiding the movement of the movable member and imparting the stress applied thereto by a forced engagement of the movable member with the mounting member abutment directly to the lock cylinder independent of the spring means. 90
10. In a lock structure of the character described, a mounting member, a lock cylinder having a key slot and being movable in the mounting member within predetermined limits upon the insertion of a key in the slot, means for releasably maintaining the lock cylinder assembled with the mounting member without interfering with its normal locking movements, said means becoming inoperative upon movement of the lock cylinder beyond one of its normal limits of movement, and means preventing movement of the lock cylinder beyond said limit of movement and including a member having a part projected into the key slot to lie in the path of a projection formed on the key, means yieldably maintaining the member in inoperative position, the insertion of the key and the engagement of its projection with the member part projected into the key slot moving the member against its yielding means to operative position to prevent movement of the lock cylinder beyond said predetermined limit of movement, and a special key adapted to free the cylinder for movement without moving the movable member whereby the lock cylinder may be moved be- 95
- yond said predetermined limit of movement to permit its withdrawal. 100
- In testimony whereof I have hereunto affixed my signature. 105
